UNITED STATES PATENT OFFICE

JULIUS G. GORDON, OF YAKIMA, WASHINGTON, ASSIGNOR OF ONE-HALF TO PETER MEINARDI, OF YAKIMA, WASHINGTON

CLOSURE MEANS FOR COLLAPSIBLE TUBES

Application filed October 28, 1931. Serial No. 571,514.

My invention relates to improvements in closure means for collapsible tubes and the primary object of my invention is to provide closure means of this nature which is arranged to be opened by pressure of the material within a collapsible tube to thereby permit any desired amount of material to be expelled from the tube and which is self closing as soon as pressure on the material within the tube is released.

Other objects of the invention are to provide closure means of this nature which is very simple and cheap in construction, which does not add materially to the cost of production of the tube, and which is reliable and efficient in operation, always opening easily under pressure to permit outlet of material from the tube and always closing quickly and tightly when pressure is released to retain the material within the tube, prevent evaporation or drying out of the material and maintain such material in a sanitary condition.

Other and more specific objects will be apparent from the following description taken in connection with the accompanying drawing.

In the drawing Fig. 1 is a top plan view of a collapsible tube constructed in accordance with my invention.

Fig. 2 is a sectional view of the same substantially on broken line 2—2 of Fig. 1, parts being shown in elevation and the lower end of the tube being broken away.

Fig. 3 is a sectional view substantially on broken line 3—3 of Fig. 2.

Fig. 4 is a fragmentary sectional view showing the discharge control valve in an open position.

Fig. 5 is a fragmentary sectional view showing the valve chamber positioned coaxial with the tube and at right angles to the position in which it is shown in the preceding figures.

Like reference numerals designate like parts throughout the several views.

Referring to Figs. 1 to 4 the numeral 6 designates a collapsible tube of the form commonly used as a receptacle for tooth paste, shaving creams, ointments and the like,

said tube being adapted to be collapsed by external pressure or rolled or folded from the bottom upwardly to force the contents out of the upper end thereof. These collapsible tubes usually have an outlet nipple on the upper end provided with a screw cap designed to be removed and replaced each time any of the contents of the tube is used. Removing and replacing the usual screw cap consumes time and requires effort. This often results in the cap being left off, thus leaving the material at the discharge opening unprotected, the result being that this material may become contaminated, or may ooze out, or may become dried and caked on the discharge end of the tube. My invention overcomes these objections by providing a collapsible tube having discharge outlet means which will be opened automatically in response to pressure of the contents of the tube and which will close automatically and without effort on the part of the user as soon as the pressure on the contents of the tube is released.

In accordance with my invention, as disclosed in Figs. 1 to 4 inclusive, I provide, in connection with the top 7 of the tube 6, a cylindrical valve chamber 8 which extends crosswise of the top of the tube and has a valve member 9 and a compression spring 10 disposed therein. A disc 11 is inserted in one end of the receptacle 8 after the valve member 9 and spring 10 have been placed therein, and said disc is secured in place by crimping or beading the edge portions of the receptacle over the edges of the disc as indicated at 12.

A valve seat 13 is formed at the other end of the valve chamber 8 and an angular passageway 14 extends from said valve seat and communicates with the interior of said collapsible tube. A discharge opening 15, through which material may discharge is provided in the wall of the valve chamber a short distance from the valve seat. The edges around said discharge opening 15 are preferably beveled off as at 16 so that substantially all of the expelled material may be wiped off each time, as by drawing a brush or the like across said opening. The dis-

charge opening 15 may be in the form of an elongated slot, as shown, or said opening may be cylindrical or of other shape.

The end of the valve 9 which engages the seat 13 is recessed as at 17 to form a relatively sharp annular edge which facilitates cutting off paste-like material and facilitates crowding the paste-like material back into the tube. A lip 18 overhangs the valve 10 slightly at the location of the discharge opening 15 when said valve is closed, thus affording a more efficient cut off means and a better seal.

The collapsible tube may be cheaply and easily cast with the several cavities and passageways 8, 14 and 15 therein. In assembling, the valve member 9 and spring 10 may be quickly and easily inserted, the disc 11 fitted into place and the portions 12 beaded over the edges of said disc to hold the same in place. All parts of the tube including the top are preferably formed of soft metal. The strength of the spring 10 may vary for materials of different consistency.

In the use of this device, pressure exerted on the tube 6 in the usual manner will instantly force the valve member 9 to the left from the closed position shown in Fig. 2 to an open position, as shown in Fig. 4, thus permitting any desired amount of material from within the tube to be quickly expelled through the opening 15, as indicated by dotted lines at 19 in Fig. 4. As soon as pressure on the material is relieved the spring 10 will close the valve member 9, thus cutting off the expelled material and effectively sealing the tube.

In the device shown in Fig. 5, the collapsible tube 6' is provided with a co-axially disposed valve chamber 8' having a piston 9' and spring 10' therein and the material is expelled through a discharge opening 15' in the side of the valve chamber 8'. The operation of this device is substantially the same as the operation of the device shown in Figs. 1 to 4, but it is not so compact nor so convenient in use.

With either form of my device the material within the tube is always instantly available and is preserved in a clean, moist and sanitary condition and all trouble and inconvenience due to the removal and replacement of screw caps is done away with.

The foregoing description and accompanying drawing clearly disclose a preferred embodiment of my invention but it will be understood that this disclosure is merely illustrative and that such changes in the invention may be made as are fairly within the scope and spirit of the following claims.

I claim:

1. In devices of the class described, a collapsible tube having a top, a tubular member having a cylindrical valve chamber formed therein, a seat at one end of said valve

chamber, said valve chamber having an opening at said seat end communicating with the interior of said tube and having a discharge opening on one side at a short distance from said seat, a cylindrical valve member movable within said valve chamber and having a concave end forming a relatively sharp annular face portion arranged to rest on said seat, and a spring yieldingly urging said valve against said seat said valve being movable by pressure of the material within said tube to uncover said discharge opening.

2. In devices of the class described, a collapsible tube having a top, a tubular member extending crosswise of said top and having a cylindrical valve chamber formed therein, a seat at one end of said valve chamber, said valve chamber having an angularly shaped opening at said seat end communicating with the interior of said tube and having a discharge opening on one side at a short distance from said seat, a cylindrical valve member movable within said valve chamber and having a concave end forming a relatively sharp annular face portion arranged to rest on said seat, and a spring yieldingly urging said valve against said seat said valve being movable by pressure of the material within said tube to uncover said discharge opening.

3. In devices of the class described, a collapsible tube having a top, a tubular member extending crosswise of said top and having a cylindrical valve chamber formed therein, a seat at one end of said valve chamber, said valve chamber having an angularly shaped opening at said seat end communicating with the interior of said tube and having a discharge opening on one side at a short distance from said seat, a cylindrical valve member movable within said valve chamber and having a concave end forming a relatively sharp annular face portion arranged to rest on said seat, a spring yieldingly urging said valve member against said seat, and a disc positioned within the end of said valve chamber removed from said seat and having the material of said tubular member clinched over the edges thereof said disc forming retaining means for one end of said spring.

The foregoing specification signed at Yakima, Wash., this 8th day of Oct. 1931.

JULIUS G. GORDON.
